UNITED STATES PATENT OFFICE.

BERNHARD TEUFER, OF CHEMNITZ, GERMANY.

PROCESS FOR THE TREATMENT OF COTTON.

1,097,377.

No Drawing.

Specification of Letters Patent. Patented May 19, 1914.

Application filed November 6, 1913. Serial No. 799,527.

To all whom it may concern:

Be it known that I, BERNHARD TEUFER, a subject of the King of Saxony, residing at Rochlitzerstrasse 11, Chemnitz, Saxony, Germany, have invented certain new and useful Improvements in Processes for the Treatment of Cotton; and I do hereby declare the following to be a full, clear, and exact description of the invention.

10 My present invention relates to a process for the treatment of cotton, by which the cotton, whether in the form of thread, yarn, or woven fabric, is given all the characteristic appearance of silk.

15 Heretofore cotton has been subjected to the well-known mercerizing process, in order to give the same a glossy appearance, and by treating mercerized cotton in a soap or an acid bath it acquires a smooth, soft feeling 20 similar to that of brightened silk. I am also aware that heretofore and prior to the time when the mercerizing process was first introduced, attempts had been made to impart a glossy appearance to cotton by subjecting 25 the same to heavy pressure known as the lustering process. This has also been accomplished by the use of sizing preparations and also, as in the so-called Eisengarn sewing thread, by a polishing and brushing 30 process. In all these various processes, however, so far as I am aware, the gloss imparted by the usual lustering process generally removes from the material the rustling or crackling sound common to silk, and 35 furthermore the spooling or other working of ordinary or mercerized yarn is made difficult from the fact that the threads so treated adhere to each other or tend to stick together. These defects are completely 40 overcome by the treatment which I have discovered, so that the threads or the strands of yarn do not adhere or stick together, and whether treated as threads or yarn, or as a woven fabric, the cotton assumes not only 45 the rustling or crackling sound, the soft, smooth and even touch, but also the gloss or shiny appearance of silk. In other words, the cotton treated in accordance with my improved process has all the characteristic 50 appearances of silk.

The process consists in first treating cotton in a bath of strong soapy solution and then treating it, while still moist, in an acid bath, such, for instance, as acetic acid, sulfuric acid, formic acid, lactic acid, or boric acid. By these treatments, the cotton assumes the rustling or crackling sound, when moved, similar to that caused by silk, and after having been so treated, the material is further subjected to high pressure by 60 means of calenders, the rolls of which are preferably provided with numerous small grooves in order to impart to the material the luster and soft, smooth silk feeling.

The process as hereinbefore described relates particularly to unmercerized cotton, and, as will be understood, the cotton may first be mercerized and then subjected to precisely the same treatment, and whether mercerized or unmercerized, the resultant effect 70 is the same; that is to say, as hereinbefore stated, the cotton subjected to my improved process assumes all the characteristic appearances of silk, and if it is desired to manufacture a dyed product, said cotton 75 may preferably be dyed before being treated by my improved process.

I claim as my invention.

1. The hereinbefore described process of preparing cotton to give the same the apparent characteristics of silk, consisting in treating the material in a soapy bath, then in an acid bath, and finally subjecting the same to heavy pressure so as to calender the same. 85

2. The hereinbefore described process of preparing cotton to give the same the apparent characteristics of silk, consisting in first mercerizing the material, then treating the same in a strong soapy bath, then in an acid bath, and finally subjecting the material to heavy pressure, so as to calender the same. 91

In testimony whereof I have signed my name to this specification, in the presence of 95 two subscribing witnesses.

BERNHARD TEUFER.

Witnesses:

E. KILBOURNE FOOTE,
EGBERT J. MAGER.
